United States Patent Office

Des. 188,200

Patented June 14, 1960

188,200

TABLE

Ernest L. Swarts and Orville B. Solie, Rockford, Ill., assignors to The Lane Company, Inc., Altavista, Va., a corporation of Virginia

Filed June 24, 1959, Ser. No. 56,527

Term of patent 14 years

(Cl. D33—14)

Fig. 1.

Fig. 2.

The essential features of the design are shown in solid lines in the drawing. The parallel vertical members shown in solid lines are shown as being identical.

We claim:

The ornamental design for a table, as shown and described.
